CLAIM

The ornamental design for a pivoting foot peg unit for motorcycles and bicycles, as shown and described.

DESCRIPTION

FIG. 1 is an exploded top view of a pivoting foot peg unit for motorcycles and bicycles showing my new design; FIG. 2 is an exploded side view of the pivoting foot peg unit for motorcycles and bicycles of FIG. 1, the opposite side view being a mirror image;

FIG. 3 is a bottom view of the pivoting foot peg unit for motorcycles and bicycles of FIG. 1 in assembled condition; FIG. 4 is an end view of the back or right end of the fixed portion of the foot peg unit for motorcycles and bicycles of FIG. 1, shown separately for clarity;

FIG. 5 is an end view of the front or left end of the pivoting portion of the pivoting foot peg unit for motorcycles and bicycles of FIG. 1, shown separately for clarity;

FIG. 6 is an exploded top view of a second embodiment of a pivoting foot peg unit for motorcycles and bicycles, with the bottom and back or right end views being the same as FIGS. 3 and 4, respectively;

FIG. 7 is an exploded side view of the pivoting foot peg unit for motorcycles and bicycles of FIG. 6, the opposite side view being a mirror image;

FIG. 8 is an end view of the front or left end of the pivoting portion of the pivoting foot peg unit for motorcycles and bicycles of FIG. 6, shown separately for clarity;

FIG. 9 is an exploded top view of a third embodiment of a pivoting foot peg unit for motorcycles and bicycles showing my design, with the bottom and back or right end views being the same as FIGS. 3 and 4, respectively;

FIG. 10 is an exploded side view of the pivoting foot peg unit for motorcycles and bicycles of FIG. 9, the opposite side view being a mirror image; and,

FIG. 11 is an end view of the front or left end of the pivoting portion of the foot peg unit for motorcycles and bicycles of FIG. 9, shown separately for clarity.
